UNITED STATES PATENT OFFICE.

WILLIS S. JONES, OF CHICAGO, ILLINOIS, ASSIGNOR TO DAVID S. WEGG,
OF CHICAGO, ILLINOIS.

RAILWAY-TIE PLATE.

SPECIFICATION forming part of Letters Patent No. 691,317, dated January 14, 1902.

Application filed July 12, 1899. Serial No. 723,540. (No model.)

To all whom it may concern:

Be it known that I, WILLIS S. JONES, a citizen of the United States, residing at Chicago, county of Cook, State of Illinois, have invented a certain new and useful Improvement 5 in Railway Tie Plates; and I declare the following to be a full, clear, and exact description of the invention, such as will enable others skilled in the art to which it pertains to make and use the same, reference being had to the accompanying drawings, which form a part of this specification.

My invention has for its object the production of a railway-tie plate which shall combine several novel and useful features.

The invention belongs to that class of plates wherein the under side of the plate is provided with tie-engaging flanges which enter and extend parallel with the grain of the tie 20 when the plate is in position thereon. It has been found by experiment that the plate of the greatest efficiency is one wherein each side edge of the plate is provided at the edge with a depending flange adapted to enter the tie and wherein one or more corresponding flanges depend from the body of the plate within the outer edges. My particular aim 25 in this invention is therefore to provide such a plate and to combine with it certain other 30 advantageous features—as, for instance, the provision on the top of the plate of sand-grooves, whereby any accumulation of sand between the rail and plate will work into the groove, and thus prevent the grinding away 35 of the bearing-surface of the plate and the rail. Now I have found that by locating these sand-grooves directly above the under side depending flanges I can materially reduce the weight of the plate without affecting 40 its strength.

The invention therefore consists, generally speaking, in the provision of a plate having depending tie-engaging flanges at its edges and one or more intermediate depending 45 flanges with grooves in the top of the plates above the flanges. My plate also embodies other novel features to be hereinafter described.

In the drawings, Figure 1 is a perspective 50 view of my plate. Fig. 2 is a cross-section

illustrating the relation of the rail-tie and tie-plate.

In carrying out my invention, A represents the plate proper, B the depending flanges at the edges of the plate, and C the intermediate 55 depending flanges.

D represents sand-grooves in the upper surface of the plate, preferably located directly above the intermediate tie-engaging 60 flanges C.

I will now call particular attention to the rounded corners *a* at each longitudinal edge of the plate. The purpose of these rounded edges is to throw the strain or weight of the rail onto the plate at a point inside the edge 65 or at a point inside the edge tie-engaging flanges. Another purpose is to prevent the wear on the edge of the plate due to what might be termed a "rocking" of the rail—that is to say, a vertical motion of the rail caused by 70 the weight of the passing wheel on the rail between the ties, thereby depressing the rail slightly at this point, while that portion of the rail above the tie is very slightly raised. This tilting of the rail is of course very slight 75 and is not perceptible, except in its effect upon the tie-plates after continued usage, but practical usage of the plate has demonstrated that there is such a tilting of the rails, and a practical use of my improved plate 80 shows that the rounded edges overcome the wear due to this slight tilting. At this point also it might be well to call attention to the particular advantage of having a tie-engaging flange at the edge. This same tilting motion of the rail which I have just described acts to loosen the plate to a great or less extent when the tie-engaging flanges are not at the edge, but with the flanges at this point and with the rounded edge the plate is held 85 firmly in place and will not rock upon the tie.

Another feature of my invention is the slight flaring out of the tie-engaging flanges B. The advantage of this is that as the flanges enter the tie they enter it in a slight 95 diagonal direction, thus locking the plate more firmly in place.

Another material advantage is the thinning of the metal, as at E. Thus while maintaining the thickness of the plate, as at E', 100

the weight is reduced for a given size and thickness of the plate by thinning the metal at the same vertical portions where the metal is more or less on edge, and a thinner body of metal can stand the pressure brought on it.

What I claim is—

1. A railway-tie plate consisting of a plate having curved edges terminating in downwardly - extending tapered, tie - engaging flanges, parallel grooves in the upper face of the plate and tapered flanges in line with and below the grooves, their upper edges reinforcing or strengthening the metal walls of the grooves, substantially as described.
- 15 2. A railway-tie plate having curved edges

terminating in downwardly - extending tapered tie-engaging flanges and provided on its upper side with one or more sand-grooves and on its under side with one or more tie-engaging flanges directly beneath the grooves, the metal comprising the walls of said grooves being thinner than the body of the plate, substantially as described.

In testimony whereof I sign this specification in the presence of two witnesses.

WILLIS S. JONES.
